INVENTOR

UNITED STATES PATENT OFFICE.

LOUIS BEGON, OF SAN FRANCISCO, CALIFORNIA.

PLOW.

SPECIFICATION forming part of Letters Patent No. 227,405, dated May 11, 1880.

Application filed December 27, 1879.

To all whom it may concern:

Be it known that I, LOUIS BEGON, of the city and county of San Francisco, and State of California, have invented an Improved 5 Standard-Plow; and I do hereby declare the following to be a full, clear, and exact description thereof.

Figure 1 is a diagram of my principle. Fig. 2 is a horizontal projection of the mold-board. 10 Fig. 3 is a perspective of the same.

My invention consists in a novel construction of the mold-board of plows, whereby I am enabled to turn over and lay the furrow-slices in the manner best adapted to the best 15 plowing. It relates only to the geometrical design of the mold-board or plow proper, and not to the beams or handles.

A D, Fig. 2, represent the land-side of the plow. D is the point of the plowshare, which 20 is wide enough at H to cut horizontally the full width, E H, of the furrow-slice. The upper curved line, D E R B, is the curve that the point E, Fig. 1, describes and follows to come to its new and lasting position, E'', to which the 25 upper corner, B, Fig. 2, of the mold-board corresponds. The corner B stands as high as the higher corner, E'', of the furrow-slice may require for being set in its proper place by the mold-board. The position of this curved line D E R B 30 and that of the bottom line, H R K, constitute the special advantages of this plow, the most important of its features being the position of point K. In order to find it we may notice that if the line E'' I', Fig. 1, of the slice now plowing is extended until it meets the bottom line, A Z, of the furrows, it will strike it at point C, 35 which is ten inches distant from point E of the next furrow-slice. This distance is equal to the depth E H, and leaves precisely at the 40 bottom of the furrow the room, E C, needed for the evolution around point E of the next furrow-slice, A B H E, the point H of which shall fall upon C, its side H B coming finally to rest upon the line C I' E'', and under an 45 angle of forty-five degrees.

The line H R K is the bottom line of the mold-board, Fig. 2. The point K of it corresponds to point C of Fig. 1, and if we join said point K to the upper corner, B, of the mold-board by the line K B (here seen in projection) 50 we shall have the back end line of the mold-

board, which will cover exactly the line C I' E'' of Fig. 1, and so will leave between itself and the slice last plowed, M O N L, just the space needed to place in it the slice now plowing, I' E'' H'' K'. This space must be, in all cases, equal to the depth, as we see from the diagram, Fig. 1, that each slice must find between the two adjoining slices a room equal to its thickness or depth—no more, no less; 60 otherwise all the accuracy of the plowing would be destroyed.

The upper and lower lines of the mold-board cross each other at point R, Fig. 2, the line I E, Fig. 1, which is gradually raised by the 65 mold-board and has assumed the position I E', when it reaches said point R and stands vertically, resting upon the mold-board, which is built also vertically along said line; then the point E' is pushed gradually to its final resting-place, E'', by the advancing curved top line of the mold-board, while in the same time the lower corner, I', of the slice finds room for itself 70 under the receding lower part of said mold-board without any portion of said furrow-slice 75 experiencing from the mold-board any pressure that could cause it to break or push it sideways to the right.

It is seen in Fig. 1 that such a recess of the lower portion of the mold-board would not be 80 needed back of point R, Fig. 2, if the slice were of such a nature as to preserve the form shown in Fig. 1; but as in most cases the ground would cave down, extending along the line I' C, and coming to rest on the bottom of the 85 furrow, it is seen also that the aforesaid recess is absolutely needed for good plowing.

The importance of the position of point K, Fig. 2, is now very apparent, as, if the mold-board were more opened at its back end, there 90 would not be room enough (ten inches) left for placing the slice now plowing between the back end line, K B, Fig. 2, of the mold-board and the one last plowed, and the consequent pressure would cause the slice to break and cave 95 into the chambers. If, on the contrary, the mold-board were narrower at the back end, there would not be room enough (ten inches) left at the bottom of the furrow for the evolution of the next slice, and hence various causes 100 for a faulty plowing.

To sum up the foregoing, I will say that the

widest part of the bottom of my mold-board is at the back end of the plowshare at point H, Fig. 2, where it is equal to the width of the furrow-slice, so as to completely cut the earth and roots on the bottom side of said slice. Still in the real construction the plowshare is a little wider at point H, to compensate for the wear. From said point H the bottom line, H K, is drawn, nearing more and more to the land-side, and terminating at point K, at a distance from said land-side equal to the depth of the plowing. The upper line of the mold-board, starting from the point D of the plowshare, rises gradually in a curved line, so that the back end of said line, which forms the upper back corner of the mold-board, stands at the height required for placing the corresponding upper point of the slice now plowing in its proper and lasting position, and at such a distance from the land-side as to have the back end line, K B, of the mold-board inclined to an angle of forty-five degrees, and leaving between itself and the slice previously plowed a distance or a space equal to the depth of the plowing, said space being needed for placing the slice now plowing between the one last plowed and the said back end of said mold-board, without any pressure or sidewise shifting of the slice.

The plowshare, which makes in the present case a single piece with the mold-board, and the land-side, as it is built here, have been so represented only for more convenience in the making of the model; but in the real construction these pieces are attached with bolts,

as usual, and can be replaced when needed, and the whole system is attached to beam and handles in some of the ways in use for plows. Also, the plow is, when desired, provided with a colter, which is attached in some of the usual ways, either along and below the beam or along and above the land-side; but said colter is not claimed to be a special part of this invention.

This plow, when applied to the work of which its construction is a counterpart, will make it perfect; but it can be also used as any other plow, on any plowing where the ratio of ten to fourteen between depth and width would not be, as it is often the case, the best to adopt, only in such cases the same perfection cannot be expected.

Having thus described my invention, what I claim as new, and desire to secure by Letters Patent, is—

The mold-board D E R B, curved as shown, and having the point H projecting, as shown, while the line H R K of the exterior lower edge of the mold-board converges toward the rear, so that the distance of the point K from the land-side equals the depth of the furrow, substantially as and for the purpose herein described.

In witness whereof I have hereunto set my hand.

LOUIS BEGON.
